SOCKET FOR SMALL ELECTRIC BULBS

Yoichi Suzuki, Takara-Cho, Kyobashi-Ku, Tokyo, Japan

Application January 3, 1935, Serial No. 199
In Japan August 12, 1934

1 Claim. (Cl. 173—328)

This invention relates to sockets for electric lamps and has special reference to a socket whereby the base of an incandescent lamp or bulb may be resiliently gripped when inserted therein.

5 The primary object of the invention is to provide a novel form of socket wherein a resilient contact member is secured with a socket body of elastic material such as rubber, the body aiding in forcing the contact member into engagement with the lamp base and the contact member and lamp base being provided with interlocking elements cooperating to prevent accidental detachment of the lamp from the socket.

10 Another object is to enable an electric bulb to be attached or detached freely to the socket body without damaging the connection of the bulb and its metal base.

15 Another object is to secure a metal shell tightly to the socket body without the help of a binding agent and not merely to enable any damage done to said metal shell of the socket to be repaired simply by drawing it out, but also to prevent the contact of the bared ends of the lead wires by means of a flexible partition.

20 Referring to the accompanying drawing which shows an embodiment of the present invention as examples,

25 Fig. 1 is a longitudinal diametric section view of the socket for a small electric bulb according to this invention;

Fig. 2 is a front elevation of a small electric bulb for use in the socket of this invention;

30 Fig. 3 is the position in which the small bulb shown in Fig. 2 is fitted to the socket shown in Fig. 1.

35 In Figs. 1 to 3, 1 is a socket body of elastic material, for instance, rubber, with a recess 3 in its lower end for receiving the metal shell 2 of the socket. Said metal shell 2 has swollen upper and lower end portions pressed strongly against the inside of the recess 3, while its central portion is curved inwardly for resilient expansion in an arc-shape in section and has an annular sunken groove 4 suitably formed to provide an annular internal rib. The base 5 of an electric bulb 5 to be inserted into the metal shell 2 of the socket is made in the form of a truncated cone and has

a projection 7 to be engaged above the rib formed by said sunken groove 4. The socket body 1 has a hole 8 at the top to receive the leg of a clip, and lead wires 9 and 10 are led in from the converging perforations at both upper sides of the socket body 1. They are then connected with a central terminal 11 and the metal shell 2 respectively.

40 According to the present invention, the metal shell 2 enlarged at the upper and lower end portions and narrow at the central portion is inserted in the recess 3 of the socket body 1 in such a manner that said upper and lower end portions engage tightly in the socket body, while the central portion is left free. Therefore, it is not only possible to hold elastically in position the base of an electric bulb, inserted in the shell of the socket, with suitable strength by giving suitable elasticity to said narrow portion, but also the connection of the shell 2 of the socket with the electric bulb 5 is secured by the engagement of the projecting lug 7 of the base 6 above the rib formed by the sunken groove 4. Moreover, the construction possesses the advantage that the bulb may be attached to or detached from the socket without any inconvenience, because of the space formed between the socket body 1 and the shell of the socket by curving the central portion of the latter inwardly.

45 It is to be noted that, in the form herein disclosed, the body is provided with a smoothly cylindrical chamber in its lower end, this chamber being open at the said lower end, and that the shell is held in this body solely by the elasticity of the body which grips tightly on the shell. This obviates the necessity of molding screw threads in the body or of providing other means than the natural body elasticity to retain the shell in place.

I claim:

50 A socket for small electric light bulbs, comprising a body of elastic material having a chamber open at its lower end, and a metal shell within said chamber and having enlarged upper and lower end portions exerting pressure against the side wall of the chamber, the intermediate portion of said shell being curved inwardly into arcuate form in section and having an inwardly pressed groove forming an internal annular rib.
